UNITED STATES PATENT OFFICE

WALTER VAN B. ROBERTS, OF PRINCETON, NEW JERSEY, ASSIGNOR TO RADIO CORPORATION OF AMERICA, A CORPORATION OF DELAWARE

STABILIZED RADIOPHONE

Application filed April 15, 1929. Serial No. 355,006.

The present invention relates to stabilized radio receivers, and, more particularly, to a receiver which is stable at all frequencies, and, additionally, has its fidelity unimpaired 5 at the low frequency end.

The distinguishing feature of the present invention involves a radio receiver which is stabilized at long wave lengths by means of capacitive reactance in the plate circuit, and 10 at short wave lengths chiefly by means of a counter feed back arrangement. The important advantage of this arrangement is that the tuning of the receiving system at the long wave lengths can be rendered abnor- 15 mally broad by the use of a sufficient amount of capacitive reactance in the plate circuit. The importance of this advantage will be readily observed, when it is realized that the ordinary neutralized receivers 20 possess too sharp a tuning characteristic at the long wave lengths for good fidelity.

At the short wave end, however, there is no necessity for any extra broadening of the tuning, and this fact fits in well with the 25 fact that the reactance of a fixed condenser in the plate circuit becomes so small at high frequencies that it does not cause broadening of the tuning. Not only that; indeed, it becomes so small that it is likely to be insuffi- 30 cient to prevent actual oscillations from occurring. Therefore, for this reason, I introduce a counter feed back in proportion as the frequency increases.

Such counter feed back may be introduced 35 in any desired fashion. For example, a magnetic counter feed back is possible, the feed back control being adjusted either fixedly, or it may be varied by the tuning condenser so as to insure stability at all frequencies 40 where stability is not obtained by reactance in the plate circuit. Again, feed back may be arranged to the grid circuit by means of a condenser (connected to the plate circuit) which controls the amount of current al- 45 lowed to flow in a coil which is either coupled to the grid circuit or a part thereof.

The capacity of this feed back condenser is adjusted to insure stability at the short wave lengths, and may if desired, be varied 50 according to frequency. However, such va-

riation of feed back with frequency will occur even if a fixed feed back condenser is used provided the feed back coil is loosely coupled to the grid circuit, because, in this case the feed back coil comes nearer to resonating with the feed back condenser at high frequencies than at low, resulting in less than neutralization at long wave lengths, if adjustment is made for complete neutralization at short waves. 55

The above discussion presents the various possibilities involved in the problem of stabilizing a tuned radio frequency radio receiver at all frequencies, emphasis being placed on the unimpairment of fidelity at 60 the low frequency end. However, I have devised a radio receiver wherein there is a transition from stabilization from long wave lengths, by means of capacitive reactance in the plate circuit, to stabilization at short 65 wave lengths chiefly by means of counter feed back, in a very novel and practical manner. In the actual construction of the receiver which I have reduced to practice, there is embodied a means for obtaining 70 neutralization at short waves, with less than full neutralization at long waves. Briefly, by using a reverse connection between the primary and secondary coils of the radio frequency transformers, and by using a type 75 of gang condenser for tuning which has its rotor grounded, there is obtained neutralization at short waves through the capacity between the stators of the gang condenser. As the wave length is increased, however, this 80 capacity between the stators is wiped out by the end plates of the rotors which enclose the stators like a shield. 85

Accordingly, it is one of the many objects of the present invention to provide a radio 90 receiver which is stable at all frequencies, has its fidelity unimpaired at the low frequency end, and comprises a tuned radio frequency receiving circuit which includes a series condenser in each of the plate circuits 95 with variable feed back which approaches complete neutralization at the short wave end.

Another important object of the invention is to provide a tuned radio receiver, which 100

is stable at all frequencies, including reverse connections between the primary and secondary coils of the radio frequency transformers and a tuning condenser so constructed and arranged in the receiving circuit that neutralization at short waves is obtained through the capacity between the stators of the condensers, this capacity between stators being wiped out by the end 10 plates of the rotors as the wave length is increased.

Other objects of the invention are to improve chiefly the simplicity and efficiency of such devices and to provide a radio receiver of the tuned radio frequency type 15 which is economical to manufacture and stable in operation.

The novel features which I believe to be characteristic of my invention are set forth 20 in particularity in the appended claims, the invention itself, however, as to both its organization and method of operation will best be understood by reference to the following description taken in connection with the 25 drawing which I have indicated diagrammatically one circuit organization whereby my invention may be carried into effect.

The drawing shows a grounded antenna circuit A, G connected to the input in the 30 first stage of a tuned radio frequency amplifier which includes a triode 1, having its filament grounded for alternating currents. The coupling between the antenna circuit and the tuned input circuit of triode 1 may 35 be varied at coil L_1 as shown in the drawing. The input circuit of triode 1 is tuned by a variable condenser C_1 , S_1 , this condenser being one of a gang of condensers mounted in the well known manner upon a single 40 shaft whereby uni-control may be obtained.

Triode 2 designates a second stage of 45 tuned radio frequency amplification, while triode 3 is a detector tube. Each of the input circuits of these three tubes is tuned by a variable condenser, as is explained before, all of these condensers being mounted on a single shaft, in a uni-control manner. The rotors C_1 , C_2 , C_3 are revolved simultaneously while the capacity between 50 the stators S_1 , S_2 , S_3 , of the gang condenser is utilized to obtain neutralization at short waves.

The plate circuits of triodes 1 and 2 are energized through choke coils I , I_1 from a 55 source, preferably, of 135 volts, it being understood that these choke coils have nothing to do with the radio frequency operation. For optimum operation a condenser C_4 of a magnitude of about .00025 microfarads is inserted in the plate circuit of tube 1 between the choke coil I , and the primary coil L_2 of the radio transformer, it being observed that a condenser C_5 of a 60 magnitude of about .0003 microfarads is similarly disposed in the plate circuit of

triode 2. These values were determined experimentally.

Resistances R_1 , R_2 are inserted in the cathode leads of triodes 1 and 2 for the purpose of obtaining bias. They have nothing to do with the radio frequency operation, it being noted that each of the resistances is shunted by condenser c or c_1 . A reverse connection is employed between the primary and secondary coils of the radio frequency transformer M_1 and M_2 , the turn ratio between coils L_2 and L_3 being about 1:4, and the ratio between primary coil L_4 and secondary coil L_5 of the radio transformer M_2 also being approximately 1:4. 75

The grid condenser C_6 is shunted by a grid resistance G inserted in the grid circuit of detector triode 3, the plate circuit of detector triode 3, being energized by a source "B". A condenser C_7 of a magnitude of about .0005 microfarads is connected between plate and cathode, the output from the detector being connected to any utilization means such as phones, loud speaker, etc. 80

The operation of the circuit disclosed has 85 been found very satisfactory, and results in stabilization at all frequencies, unimpaired fidelity being secured, in particular, at the low frequency end. It will be observed that neutralization is obtained at short 90 waves through the capacity between the stators S_1 , S_2 and S_3 of the gang condenser, it being noted that the rotors C_1 , C_2 , C_3 of the said gang condenser are all grounded and uni-controlled. 95

As the wave length is increased, this capacity between the stators is wiped out by the end plates of the rotors which enclose the stators like a shield. This type of condenser is well known, and it is believed that the diagrammatic showing thereof will readily teach those skilled in the art the manner of employing the same in the circuit of the type disclosed. It will be noted that the series condenser C_4 , C_5 in the plate circuits of each of the tubes 1, 2 combine with the variable feed back to produce approximately complete neutralization at the short wave end, it being especially observed that less than full neutralization is employed at long waves. It will thus be obvious that the distinguishing feature of the present receiver is the transition from stabilization at long wave lengths chiefly by means of capacity reactance in the plate circuit to neutralization at short waves chiefly by means of counter feed back. 105

While I have indicated and described one system for carrying my invention into effect, it will be apparent to one skilled in the art that my invention is by no means limited to the particular organization shown and described, but that many more modifications in the circuit arrangement may be used, as well as in the apparatus employed, 110 115 120 125 130

without departing from the scope of my invention as set forth in the appended claims.

What I claim is:

1. A radio receiver comprising signal energy collecting means, a plurality of tuned radio frequency amplification stages, each of said stages including an electron discharge device, a series condenser in the anode circuit of each of said devices, a uni-controlled tuning capacity common to the input circuits of each of said stages, and means including the capacitance between the stators of said tuning capacity for producing variable feed back which approaches complete neutralization at the short wave end. 5
2. A radio receiver including a plurality of tuned radio frequency amplifier stages, each of said stages including a fixed condenser in its plate circuit, a uni-control condenser common to the input circuits of said stages, means including the capacitance between the stators of the uni-control condenser for introducing a counter feed back in proportion as the frequency increases, for obtaining neutralization at short waves. 10
3. A radio receiver which is stabilized at all frequencies and has its fidelity unimpaired at its low frequency end comprising a signal energy collecting means, a plurality of amplifying stages coupled thereto, each of said stages including a triode having a fixed capacitance in its plate circuit, the coupling between stages comprising a reverse coupling between the primary and secondary coils of the radio frequency transformers, a uni-control condenser having the rotors thereof grounded, and common to the input circuits of said stages, the circuit being so arranged that neutralization at short wave lengths is obtained through the capacity between the stators of the uni-control condenser. 15
4. In combination, a plurality of resonant high frequency circuits, an electron discharge repeater for coupling each succeeding pair of circuits, a common variable capacitance for tuning all of said circuits through a range of frequencies, means for counteracting feed back of energy through said repeaters, and additional means, including capacitive reactance produced during a portion of the variation of said common capacitance, for aiding said counteracting means during tuning to the higher portion of said range. 20
5. A radio receiver comprising a plurality of tuned amplifier stages, each stage including a repeater, the output circuit of each repeater being coupled to the input circuit of a succeeding repeater by an inductive coupling having a turn ratio, between primary and secondary, of about 1:4, a uni-controlled gang of variable condensers connected for tuning the input circuits of said repeaters, and additional means, including the capacity between at least one stator in each condenser of said gang, for obtaining neutralization at short wave lengths. 25
6. In combination, a plurality of tunable oscillation circuits, an electron discharge tube coupling said circuits, a uni-control, variable gang condenser for simultaneously and similarly tuning said circuits to a desired frequency in a predetermined frequency range, means for effectively counteracting feed-back of energy between said circuits at the low frequency end of said range, and additional means, including capacitive reactance produced between portions of said gang condenser during a portion of the variation thereof, for effectively counteracting feed-back of energy between the circuits at said last named portion. 30
7. In combination, a plurality of tunable oscillatory circuits, a space discharge tube coupling said circuits, means for simultaneously and similarly tuning said circuits to a desired frequency in a predetermined frequency range, reactive means for effectively counteracting feed-back of energy between said circuits at the low frequency end of said range, and additional reactive means of like sign as said first reactive means, operative during adjustment of said tuning means to the high frequency end of said range, for effectively counteracting feed-back of energy between the circuits at said high frequency end. 35
